FIREARM

Crawford C. Loomis, Ilion, N. Y., assignor to
Remington Arms Company, Inc., a corporation
of Delaware

Application August 1, 1933, Serial No. 683,110

5 Claims. (Cl. 42—70)

This invention relates to firearms, and contemplates certain mechanisms by the use of which the firing mechanism is effectively held against such movement as would fire a shell or cartridge in the chamber at all times when the breech is not closed and securely locked.

For the purpose of illustration, the invention has been shown in the drawing and will be described as applied to a multiple-barrel single-trigger firearm of the type shown in this applicant's prior application Serial No. 616,234, filed June 9, 1932. Reference may be had to said application for a detailed description of any mechanism not herein fully described and illustrated.

The firearm shown in the prior application is of the superposed barrel upward tilting breech type. A firing hammer and hammer controlling sear are associated with each barrel, but the two sears are adapted to be selectively displaced to release their respective firing hammers by successive pulls of a single trigger. The firearm likewise comprises a safety mechanism which is manually controllable by a finger piece on the top of the tang and is movable either forward or rearward from an intermediate "safe" position. When it is moved forward from "safe" position, to permit firing, the movement of unlocking the breech preparatory to opening the same to remove fired shells or cartridges and insert fresh ones restores the safety device to "safe" position. However, if the arm is placed in firing condition by moving the safety device to the rear from its "safe" position it is not affected by the unlocking or opening of the breech. In this condition it becomes theoretically possible to release the firing hammers at a time when there are unfired shells in one or both of the chambers and the firing pins are so aligned with these shells as to strike their primers, but the breech mechanism is not locked. An arm which can thus be fired, without a positive locking of the breech mechanism, is potentially dangerous, and it is an object of this invention to provide a locking device for the firing mechanism which will positively prevent the release of either of the firing hammers unless the breech is not only closed but securely locked.

A further object of the invention is to provide a safety device, in addition to the manually operated safety device shown in applicant's prior application, which is particularly adapted for use with a single trigger mechanism.

A further object of the invention is to provide a safety device under the direct and positive control of the breech locking mechanism which has a positive engagement with each of the sears,

whereby the hammer releasing movement of any sear is definitely prevented at any time when the breech is unlocked.

A further object of the invention is to provide means, associated with the sear locking element, which prevents over or abnormal movement of any sear when the hammer controlled by such sear is in its fired position. This feature is of especial importance in conjunction with single trigger devices, inasmuch as a sear which has been displaced by a pull of the trigger is thereafter disconnected from the trigger and, in the absence of a restraining device, is free to move forward under the action of its spring to such a position as to block the return of the hammer to cocked position.

A further object of the invention is to provide means for definitely locking the manual safe against displacement by recoil, and to associate such a locking device with the trigger.

With these and other incidental objects in view, the invention consists in the novel mechanisms, combinations and arrangements of parts, a representative embodiment of which has been shown in the accompanying drawing and will be hereinafter described.

In the drawing:

Fig. 1 is a fragmentary, longitudinal, sectional elevation of a firearm having one form of the present invention applied thereto.

Fig. 2 is a transverse section, substantially on the line 2—2 of Fig. 1.

Fig. 3 is a fragmentary, sectional, side elevation, substantially similar to Fig. 1 but showing the breech mechanism unlocked and the sears positively locked in engagement with their respective hammers.

Fig. 4 is a fragmentary, longitudinal, sectional elevation showing the trigger depressed and the manual safe locked.

The illustrative firearms shown in the drawing comprise superposed barrels 10 and 11 hinged to a frame 12 which supports fire control mechanism. Said frame comprises an upstanding partition 13 forming a breech closure for the barrels, and perforated to admit firing pins which pass through a supporting block 14 suitably held in the frame 12. The firing pins are adapted to be struck by firing hammers 15 pivoted at 16 in supports extending from the bottom plate of the frame 12. Each of the firing hammers 15 is under the control of a sear 17 provided with an elongated aperture 18 which receives a pivot pin

19 common to the two sears and held in sear 55

housing plates 20 secured to the base or trigger plate 21 of the frame 12.

A single trigger 22 is pivoted at 23, and a connector 24 is carried on a longitudinal pivot in the trigger. Said connector 24 is arranged to be shifted from a position beneath either of the sears to a position beneath the other sear under the joint control of a manual shifter 25 and right and left actuators 26 pivoted at 27 and controlled respectively by the right and left firing hammers 15. The control of said connector is fully described in applicant's prior application, heretofore identified. It is sufficient to state here that the initial position of the connector is determined by the transverse position of the manual shifter 25 and if, for example, the shifter is so positioned that the connector is beneath the right hand sear a pull of the trigger will result in displacement of this sear and release of the right hand hammer. Upon its movement to firing position, said hammer acts upon the associated actuator 26 in such a way as to rock the connector 24 about its pivot and place it beneath the left hand sear. Each sear is urged forward (toward its associated hammer) by a sear spring 28. The connector having been shifted from beneath the right hand sear said sear tends to rock forward into a position occupied by a part of the right hand hammer when this hammer is cocked.

The present invention comprises a device for preventing such over-movement of the sear, which device will be presently described.

Extending between the two sears 17 is a safety bar 29 comprising an elongated guide slot 30 which receives the sear pivot pin 19. Upon opposite sides of such safety bar are lugs 31 which in one position of the safety bar stand beneath the inturned ends 32 of the two sears, thereby blocking hammer releasing movement of said sears. At its upper and rear end the safety bar is suitably joined to a plate 33 which extends upwardly through the top plate or tang 34 of the frame and carries at its upper end a finger piece 35. Said finger piece, and with it the safety bar, may be shifted to any one of three positions; a forward firing position, an intermediate "safe" position, and a rearward firing position. It will be apparent that the gun is in firing condition whenever the safety bar lugs 31 are not beneath the inturned ends 32 of the sears, that is, when said lugs are either in front or in the rear of said sear ends. The construction of the safety mechanism and its operating finger piece are more fully described in the application heretofore identified.

An alternative form of manual "safe" and a modified control by the breech locking mechanism are described in this applicant's prior application, Serial No. 671,626, filed May 18, 1933, and it will be understood that the devices of the present invention are applicable to guns containing either of these safety devices, as well as many others.

If the safety mechanism as heretofore described is placed in its forward firing position it will be restored to "safe" position upon the unlocking of the breech mechanism. The breech locking devices shown in the drawing comprise an arcuate cover form of lock 36 extending over and partially surrounding the upper barrel 10. This sliding breech cover 36 is connected at 37 with a manually operable "top lever" 38 and is retracted to unlock the breech by lateral movement of said top lever. Likewise connected to the top lever is a rearwardly and downwardly extending plunger 39 which, together with the top lever, is urged

forward by a spring 40 encircling a section of the plunger 39 and engaging an abutment 41 extending inward and downward from the tang 34. If the safety mechanism is in its forward firing position, the rearward end of the plunger 39 will engage a part of the safety mechanism, such as the forward edge of the plate 33, and by such engagement restore the safety mechanism to its intermediate or "safe" position. However, if the safety mechanism has been moved to the rear from "safe" position it is not restored when the breech is unlocked, but remains in its rearward ineffective position, leaving the sears free for hammer releasing movement by depression of the trigger.

The present invention comprises the provision of a device which will positively prevent hammer releasing movement of the sears while the breech is unlocked, but will automatically release the sears, placing the gun in firing condition, when the breech becomes locked and firing is safe. One form of this device is as follows: A cross-pin 42 extending from the plunger 39 near its rear end is received in the forked end of a lever arm 43 pivoted at 44 in a part of the sear housing plates which extends above the rear ends of the sears. Below the plunger 39, the member 43 is formed as a yoke comprising a transversely extending part 45, from which a second arm 43R, similar to the first, extends downwardly and is received on the pivot pin 44. Arms 43 and 43R are aligned with and act in the same manner upon the left and right hand sears, respectively, hence only arm 43 will be described. The lower end of said arm comprises a recess, bounded by the part of the arm adjacent the pivot 44 and a finger 47. When the breech is closed and locked, the arm 43 occupies the position shown in Fig. 1. The recess in its lower end stands in the rear and slightly above the end of the sear, and the sear is free to move to disengage its hammer.

The condition of these parts when the breech is unlocked is illustrated in Fig. 3. By the rearward movement of plunger 39, pin 42 has been carried to the rear, rocking the arm 43 about pivot 44 and moving the finger 47 forward and downward until it stands beneath the tail of the associated sear 17, thereby preventing such rocking of the sear as would effect release of its firing hammer. When the breech lock moves forward, plunger 39 likewise moves forward, restoring member 43 to the Fig. 1 position and leaving the sear free. Moreover, the part of arm 43 adjacent the pivot 44 lies immediately above and in close proximity to the upper surface of the sear tail, and stops the sear from over forward movement into a position which would interfere with the return of the hammer to cocked position. A fully automatic and entirely positive control of the sears, rendering the gun entirely incapable of being fired when the breech is unlocked but releasing it immediately for firing when the breech becomes locked, is thus provided.

The invention further contemplates means for positively locking the manual safe during the depression of the trigger. As heretofore described, the manual safe is arranged with two firing positions on opposite sides of the "safe" position, and when in the rearmost firing position it is in no way controlled or affected by the unlocking movement of the breech bolt. It has been found that when the gun is fired with the safe in the rearward firing position the recoil of the frame is sometimes sufficient to throw the manual safe forward to "safe" position, so that the fire control mechanism is unintentionally blocked against

firing movement. To obviate this malfunctioning, applicant has provided for the locking of the safety bar 29 by the trigger when the trigger is depressed.

5 The safety bar comprises notches 48 and 49 (Fig. 3) adapted to receive a projection 50 on the trigger. When the manual safe is in forward firing position the notch 49 is aligned with the projection 50 and when it is in rearward firing position the notch 48 is aligned with the projection 50. Upon depression of the trigger to fire the gun the projection 50 enters the notch with which it is aligned, thereby positively holding the safety bar 29 against movement in either direction as long as the trigger is held depressed.

10 The embodiment of the invention herein described and illustrated in the drawing is merely a typical and representative one, the invention being susceptible of embodiment in other forms, 20 all falling within the scope of the appended claims.

What is claimed is:

1. In a firearm of the tilting breech type, in combination, a breech locking mechanism, a firing hammer having a cocked position and a fired position, a sear, a safety device for holding said sear in engagement with said firing hammer when in cocked position, and a supplemental safety device actuated by said breech locking mechanism and engaging said sear to hold the same against both forward and backward rotation when the breech is unlocked.

2. In a firearm of the tilting breech type, in combination, a breech locking mechanism, a firing hammer having a cocked position and a fired position, a sear, a safety device for holding said sear in engagement with said firing hammer when in cocked position, and a supplemental safety device actuated by said breech locking mechanism and engaging said sear to hold the same against any movement when the breech is unlocked, said supplemental safety device likewise preventing over-movement of said sear when said hammer is in fired position.

3. In a firearm of the tilting breech type, in combination, a breech locking mechanism, a plunger connected to move with said breech locking mechanism, a firing hammer having a cocked position and a fired position, a sear, a manual safety device for holding said sear in engagement with said hammer, and a supplemental safety device acting to prevent over-movement of said sear when said hammer is in fired position and movable by said plunger to prevent any movement of said sear when the breech is unlocked.

4. In a firearm, in combination, a breech locking mechanism, a plurality of firing hammers, a sear for each of said firing hammers, said sears being mounted between fixed sear housing plates, a manually operable safety mechanism, a single trigger a connector on said trigger adapted for selective engagement with any of said sears and to be moved toward another sear after the fall of the hammer controlled by the first sear and a supplemental safety device comprising a lever pivoted in said sear housing plates and controlled by said breech locking mechanism to prevent any movement of any of said sears when the breech is unlocked.

5. In a firearm, in combination, a breech locking mechanism, a plurality of firing hammers each movable from a cocked position to a fired position, a sear for each of said firing hammers, said sears being mounted between fixed sear housing plates, a manually operable safety mechanism, a single trigger, a connector on said trigger adapted for selective engagement with any of said sears and to be moved toward another sear after the fall of the hammer controlled by the first sear, and a supplemental safety device comprising a lever pivoted in said sear housing plates, said supplemental safety device acting to prevent over-movement of each of said sears when its hammer is in fired position and being controlled by said breech locking mechanism to prevent hammer releasing movement of any of said sears when the breech is unlocked.
